Primary Examiner — Wan Laymon*Assistant Examiner* — Clint A Samuel(74) *Attorney, Agent, or Firm* — Steven N. Fox, Esq.(57) **CLAIM**

The ornamental design for a ring light, as shown and described.

DESCRIPTION

FIG. 1 is a front perspective view of a ring light according to the present invention shown when a light diffuser component is active;

FIG. 2 is a front perspective view of the ring light when the light diffuser component is inactive;

FIG. 3 is a front view of the ring light when the light diffuser component is active;

FIG. 4 is a rear view thereof;

FIG. 5 is a left side view thereof;

FIG. 6 is a right side view thereof;

FIG. 7 is a bottom view thereof; and,

FIG. 8 is a top view thereof.

The broken lines show environmental structure and form no part of the claimed design.
